UNITED STATES PATENT OFFICE.

CHARLES HARRY NEWBOLD, OF LONDON, ENGLAND.

SPECTACLES.

No. 815,975.

Specification of Letters Patent.

Patented March 27, 1906.

Application filed November 26, 1904, Serial No. 234,383.

To all whom it may concern:

Be it known that I, HARRY NEWBOLD, a subject of the King of Great Britain, residing at 46 and 48 Goswell road, London, England, have invented new and useful Improvements in Pince-Nez, Spectacles, and the Like, of which the following is a specification.

My invention relates to frameless pince-nez, spectacles, and the like, and comprises the novel form of mount hereinafter described for the attachment of the bridge, side arms, and the like.

A mount constructed according to my invention comprises a stirrup which embraces the lens and a pin which is passed through a hole in the lens and notched to receive the ends of the stirrup. The sides of each stirrup are preferably formed of wire attached to a base-plate, and in the base-plate is inserted a screw designed to bear against the edge of the glass or lens and draw the stirrup tightly into the notches of the pin. This base-plate also serves for the attachment of the bridge or the joint for the side bars or of any other device to be carried on the lens.

To enable my invention to be fully understood, I will describe the same by reference to the accompanying drawings, in which—

Figure 1 is a front view of a pair of pince-nez to which my improvements are applied. Fig. 2 is an elevation of the attachment drawn to a larger scale than Fig. 1, and Fig. 3 is a section on the line 3 3, Fig. 2. Fig. 4 is a plan of the stirrup detached, and Fig. 5 is a plan view of the notched pin with which the stirrup engages.

The stirrup of my improved attachment consists of two side loops *a a*, attached to a base *b*, the distance between the said side loops being adapted to the particular lens *c* or lenses to which the attachment is to be applied.

d is the pin with which the loop is designed to engage, the said pin being fitted into a hole in the lens *c* and having in it two notches or grooves *e e*, with which the ends of the loops *a a* will engage.

f is a screw which is inserted through the base *b* and which by pressing against the edge of the lens, as shown in Figs. 2 and 3, draws the loops *a a* into the said notches *e e* with sufficient firmness to hold the attachment rigid.

In applying the attachment to a lens the

screw *f* is drawn back to its full extent or as far as may be necessary, and then the stirrup is placed over the edge of the lens, so that the hole for receiving the pin *d* is inside the loops. The pin *d* is then inserted into the hole in the lens, whereupon the screw *f* is tightened to draw the loops into the notches *e e* of the pin and to secure the attachment.

g is an eye or socket which is formed upon the base *b* and to which the desired fittings can be connected. As shown in the drawings, the socket is represented as carrying the bridge *h* of a pair of pince-nez; but it will be obvious that the side bars of spectacles can be connected to the said socket or a ring for a chain or cord, as desired.

In the drawings the side loops *a a* are represented as being composed of open-wire frames; but it will be understood that they may be composed of plates, provided that the necessary holes are formed through which the pin *d* can be passed; also, instead of using the screw *f* for fixing the stirrup or attachment a wedge or other means can be made use of.

Having now particularly described and ascertained the nature of my said invention and in what manner the same is to be performed, I declare that what I claim is

1. In a device of the class described, the combination with a pin constructed to pass through the lens, said pin being provided with notches, a stirrup embracing the edge of the lens and provided with loops constructed to engage with said notches in said pin and an adjusting-screw passing through said stirrup and bearing against the edge of the lens whereby said stirrup may be forced to tightly grip said pin, substantially as described.

2. In a device of the class described, the combination with a pin constructed to pass through the lens, said pin being provided with notches, a stirrup embracing the edge of the lens and provided with loops constructed to engage with said notches in said pin, an adjusting-screw passing through said stirrup and bearing against the edge of the lens whereby said stirrup may be forced to tightly grip said pin and means for securing the bridge and side bars to said stirrup, substantially as described.

3. In a device of the class described, the combination with a pin constructed to pass

2

through the lens, said pin being provided with notches, a stirrup embracing the edge of the lens and provided with loops constructed to engage with said notches in said pin, an adjusting-screw passing through said stirrup and bearing against the edge of the lens whereby said stirrup may be forced to tightly

grip said pin, and an eye on said stirrup, substantially as and for the purpose described.

HARRY NEWBOLD.
